UNITED STATES PATENT OFFICE.

JOHN LACKO, OF PORTAGE, PENNSYLVANIA.

CARBID-LAMP TOOL.

1,360,232.

Specification of Letters Patent. Patented Nov. 23, 1920.

Application filed April 7, 1920. Serial No. 371,913.

To all whom it may concern:

Be it known that I, JOHN LACKO, a citizen of Czechoslovakia, residing at Portage, in the county of Cambria and State of Pennsylvania, have invented certain new and useful improvements in Carbid-Lamp Tools, of which the following is a specification.

This invention relates to certain new and 10 useful improvements in carbid lamp tools particularly adapted to provide in a compact and readily accessible manner means for cleaning the carbid container, means for cleaning the perforations of the burner of 15 the lamp, and means for igniting the lamp.

The primary object of the invention is to 20 provide a tool of the above character which is extremely efficient and durable in construction as well as capable of being cheaply 25 and easily manufactured and which embodies means for permitting the tool to be readily clasped upon the peak of a miner's cap or other article of clothing for carrying the tool when not in use.

Further objects will appear as the nature 30 of the invention is better understood, and the same consists in the novel form, combination and arrangement of parts hereinafter fully described, shown in the accompanying drawing and claimed.

In the drawing wherein like reference characters designate corresponding parts throughout the several views,

Figure 1 is a view partly in side elevation 35 and partly broken away of a tool constructed in accordance with the present invention,

Fig. 2 is an edge elevational view, partly broken away of the device shown in Fig. 1,

Fig. 3 is a top plan view thereof,

Fig. 4 is a transverse fragmentary sectional view on a slightly larger scale illustrating the igniting device and the manner 40 of mounting the same upon the handle of the tool, and

Fig. 5 is an enlarged view partly in side elevation and partly in section and taken substantially upon line V—V of Fig. 3.

Referring more in detail to the several views, the present invention embodies a straight metallic shank 5 which is reduced at its free end to provide a blade 6 serviceable in removing the hard carbid from the carbid container of a carbid lamp, the other end of the shank 5 being return-bent to pro-

vide a handle in the form of a loop 7, the 55 other end of the device terminating in a tongue 8 lying closely to the shank 5 as shown in Fig. 1. The loop 7 is preferably resilient and the free end of the tongue 8 is slightly curved outwardly as at 9 so that 60 the peak of a miner's cap or the like may be sprung between the shank 5 and the tongue 8 for carrying the tool when not in use. A tubular container 10 is formed in any suitable manner upon the end portion of the 65 shank 5 adjacent the handle forming loop 7, and this container is adapted to hold a suitable pin or needle 11 serviceable in removing obstructions from the perforations in the burner of a carbid lamp, the needle 11 70 being provided with an enlargement 12 adjacent one end for being grasped by the user of the needle. A suitable slip cover or cap 13 is provided for the open upper end of the container 10.

A sheet metal bracket 14 rests upon the 75 upper end of the loop 7 and extends downwardly along one edge of the latter as at 15 then under the same as at 16, and then downwardly within the loop 7 as at 17 where a 80 suitable shaft 18 is journaled therein. The bracket 14 extends laterally beyond the opposite edge of the top portion of the loop 7 as at 19 and is provided in this extended end with a screw threaded aperture as at 20 85 into which is screwed a hollow plug 21 having a depending leg 22 in which the other end of the shaft 18 is journaled. A suitable milled or peripherally roughened wheel 23 is fastened upon the shaft 18 adjacent the leg 90 22, and a stick of flint 24 or equivalent material is slidably disposed within the plug 21 and has its lower end yieldably pressed into engagement with the periphery of the wheel 23 by means of a helical spring 25 95 which is interposed between the cap 26 of the plug 21 and the upper end of the stick 24. A lever 27 is fastened upon the shaft 18 adjacent the depending leg 17 of the bracket 14, and said lever or arm 27 extends 100 through an elongated slot 28 which is provided in the upper and outer portions of the loop 7 as will clearly appear in Figs. 1, 2 and 3. The hub portion of the lever 27 is provided with a downwardly extending 105 ear 29 to which one end of a tension spring 30 is attached, the other end of said spring being attached as at 31 to the lower portion

2

of the loop 7. It will thus be seen that when the lever 27 is swung downwardly manually as indicated by the arrow lines in Fig. 1 against the action of the spring 30, the 5 wheel 23 is rotated and by reason of the contact of the stick 24 therewith, a spark or sparks are produced which are serviceable for igniting a carbid lamp as will be apparent. The bracket 14 may be fastened to the 10 loop 7 by any suitable means, but I prefer to do this by means of stud screws 32 which pass through suitable perforations provided in the bracket 14 and are threaded into suitable sockets 33 formed in the upper portion 15 of the loop 7 as shown in Figs. 3 and 5. The threaded sockets 33 are preferably arranged in pairs so that the bracket 14 may be secured in any one of a number of positions farther from or nearer to the needle container 10. One purpose of this adjustment 20 will be understood from the fact that when the bracket 14 is positioned as seen in Fig. 3, the forward edge 34 of said bracket will form a stop for the lever 27 and limit its 25 upward movement to a predetermined position, whereas if said bracket 14 were positioned nearer the needle container 10, the lever 27 could be moved upwardly to a further extent by the spring 30 before the same 30 contacts the edge 34 of the bracket 14, and when the lever 27 is subsequently pulled downwardly, a further rotary movement is permitted the wheel 23 for insuring a 35 production of a larger number of sparks. It is, of course, to be understood that the spring 30 normally moves the lever to and holds the same in a raised position, while the lever 27 is effectively guided and held against lateral movement within the slot 28.

40 It is believed that the construction and operation as well as the advantages of the present invention will be readily understood and appreciated by those skilled in the art from the foregoing description.

45 Minor changes may be made without de-

parting from the spirit and scope of the invention as claimed.

What I claim as new is:—

1. In a carbid lamp tool of the class described, a metallic shank formed with a 50 carbid container cleaning blade on one end thereof and having its opposite end returnbent to provide a handle forming loop with a resilient tongue extending therefrom adjacent to and longitudinally of the shank 55 whereby the peak of a cap or the like may be sprung between said shank and said tongue for carrying the tool when not in use, the upper and outer portions of said loop being longitudinally slotted, and an 60 igniter carrying bracket mounted upon the upper portion of said loop, said igniter including a lever projecting outwardly through said slot in said loop.

2. In a carbid lamp tool of the class described, a metallic shank formed with a carbid container cleaning blade on one end thereof and having its opposite end returnbent to provide a handle forming loop with a resilient tongue extending therefrom adjacent to and longitudinally of the shank whereby the peak of a cap or the like may be sprung between said shank and said tongue for carrying the tool when not in use, the upper and outer portions of said 70 loop being longitudinally slotted, an igniter carrying bracket mounted upon the upper portion of said loop, said igniter including a lever projecting outwardly through said slot in said loop, a spring attached to said 75 lever and to the lower portion of said loop for normally holding the lever in its upper limit of movement, and means adjustably connecting the igniter carrying bracket to the loop for permitting the said lever to 80 move through arcuate paths of various lengths.

In testimony whereof I affix my signature.

JOHN LACKO.
